UNITED STATES PATENT OFFICE.

ADOLPH GRAMLICH, OF NEW YORK, N. Y.

DESIGN FOR A FLAG, PENNANT, SIGN, EMBLEM, OR ARTICLE OF A SIMILAR NATURE.

53,298.

Specification for Design.

Patented May 13, 1919.

Application filed September 16, 1918. Serial No. 254,365. Term of patent 3½ years.

To all whom it may concern:

Be it known that I, ADOLPH GRAMLICH, a citizen of the United States, and resident of 1999 Clinton avenue, in the county of Bronx and State of New York, have invented a certain new, original, and ornamental Design for Flags, Pennants, Signs, Emblems, or Articles of a Similar Nature, of which the following is a specification, reference being had to the accompanying drawing, forming a part thereof.

The figure is a plain view of a flag, showing my new design. Said design is of a service flag and consists of a center field of white in the form of a T, upon which is placed a blue star; the cross bar of the T being bordered by a red edge, and the perpendicular, or center stripe, bordered on one side by a red stripe and on the other side by a blue stripe.

I claim.

The ornamental design for a flag, pennant, sign, emblem, or article of a similar nature as shown.

Signed at 1999 Clinton avenue, in the county of Bronx and State of New York, this twelfth day of September, A. D. 1918.

ADOLPH GRAMLICH.
